LATCH

Filed April 27, 1925

Patented Aug. 13, 1929.

UNITED STATES PATENT OFFICE.

HAROLD F. WARDWELL, OF DETROIT, MICHIGAN, ASSIGNOR TO DETROIT STEEL PRODUCTS COMPANY, OF DETROIT, MICHIGAN, A CORPORATION OF MICHIGAN.

LATCH.

Application filed April 27, 1925. Serial No. 26,228.

This invention relates to latches, and more particularly to latches for side wall vents and the like.

The invention has an object to simplify, 5 render more efficient, and improve generally devices of this character and to produce a gravity cam latch designed more especially for side wall vents and the like.

The details of construction of an illustrative embodiment, as well as the advantages 10 of the invention, will be made more apparent as this description proceeds, especially when considered in connection with the accompanying drawings wherein.

15 Figure 1 is a front elevation of a fragmentary portion of a side wall vent and frame showing the application of my invention.

Figure 2 is a top plan view,

Figure 3 is a vertical transverse section 20 taken substantially on the plane indicated by the line 3-3 in Figure 1, and

Figure 4 is a front elevation of a slightly modified form of construction.

Referring now particularly to the drawings wherein like reference characters indicate like parts, it will be noted that there is 25 illustrated a side wall vent or sash 10, while the reference character 11 indicates the window frame. While it will be immediately 30 obvious that any desired sash and frame construction may be employed it will be noted that the cross-sectional shape of the sash and frame 10 and 11 includes in each instance abutting surfaces 13 and 14. With a construction such as this the sash has a double 35 engagement with the frame throughout, thus insuring a weather-proof joint.

Mounted upon one of the frame members, 40 preferably and herein shown as the stationary frame member 11, is a keeper 15. This keeper plate is rigidly secured to the frame 11 for instance to the central portion 13' thereof by means of rivets 16 or the like, and extends outwardly therefrom as shown 45 in Figure 3. The flange of the sash 10 is preferably cut away as shown at 10' for the reception of the keeper plate.

The keeper plate has one face 17 thereof bevelled, this bevelled portion being interrupted by a latch recess or depression 18 into 50 which the latch member is adapted to engage. One wall 19 of this recess 18 is inclined or bevelled with respect to the path

of movement of the latch member yet to be described, which latch member is adapted to 55 swing in a path perpendicularly to the plane and at right angles to the longitudinal axis of the keeper plate 15.

Mounted upon the sash 10 is an escutcheon plate 20 constituting the means for mounting the latch member. The latch member 12 consists of a latch portion or element 21 and an operating portion consisting preferably of a weighted handle 22. In the embodiment of the invention herein shown the 65 latch member 21 and handle 22 are shown as formed of one piece provided with an apertured hub portion 23 through which the headed stub shaft or pin 24 is passed for mounting the member 12 upon escutcheon 70 plate 20.

Latch element 21 is provided with a bevelled or inclined face 25 adapted for engagement with the inclined face 17 of keeper 15 during the initial engagement of the latch 75 element with the keeper. A projection 26 formed on the escutcheon plate 20 constitutes a stop which engages a shouldered portion 27 of the latch element 21 for defining the 80 position of rest of the latch member during its inoperative periods. With the shoulder 27 engaging the stop 26 the bevelled face 25 will be positioned to engage the inclined face 17 of the keeper when the sash 10 is moved to closed position. It will be understood 85 that handle 22, which is weighted, tends by gravity to move the latch element 21 past the determined point of rest so that during the inoperative position of the parts the shoulder 27 will be in engagement with the 90 stop 26.

Latch member 12 is formed with openings 28 and 29 in the latch element 21 and handle 22 respectively. Flexible members 30 and 31, such as chains or the like, are connected 95 at these points to the latch element and handle. These two flexible members are connected together as at 32 and continue as a single flexible operating member 33. With this arrangement it is possible to swing the 100 latch member about its pivot 24 in either direction merely by inclining the direction of pull exerted upon the operating member 33.

Consequently when the sash 10 has been 105 swung to closed position and the latch element 21 has entered the recess 18 in the

keeper plate the sash may be forced firmly against the frame 11 by exerting a pull upon the flexible member 31 and handle 22, whereupon latch member 21 is caused to ride along inclined face 19, the resulting wedging action causing a firm engagement of the sash with the frame. When it is desired to open the window a pull is exerted upon flexible member 30 to swing the latch member about 10 its pivot in the opposite direction and out of engagement with the keeper plate, whereupon the window may be swung about its horizontal pivots away from the frame into open position.

15 In Figure 4 a slightly modified form of construction is shown in which the latch portion 21 of latch member 12 is formed with an abrupt face 34 extending substantially from the hub portion 23, this abrupt face 20 engaging the recess in the keeper 15 as well as the stop 26 on the plate 20. In other respects this form of construction is substantially similar to the one previously described.

While the one embodiment of the invention together with a slight modification thereof, has been illustrated and described herein in some detail, it will be immediately apparent to those skilled in the art that various modifications might be resorted to 30 without departing from the spirit and scope of this invention, and to this end reservation is made to make such changes as may come within the purview of the accompanying claims.

35 What I claim as my invention is:

1. In a latch construction, a keeper, a 40 swingingly mounted latch member oscillatable by gravity toward latching position, said keeper being formed with a latch recess having one wall thereof inclined with reference 45 to the path of oscillation of said latch member, and means consisting of a member connected to said latch member at separated points for forcing said latch member into engagement with the inclined wall of said latch recess and for releasing said member, said member having a free end whereby the same may be actuated.

2. A gravity latch for swinging windows 50 and the like comprising, a keeper plate adapted to be attached to a window frame, a swingingly mounted latch member adapted to be mounted upon a sash, said keeper being formed with a latch recess into which said 55 latch member is movable by gravity actuated means, one wall of said recess and one face of said latch member co-operating to produce a relative wedging action therebetween and a single operating member having 60 branches connected to said latch member at both ends for forcing said latch member into wedging position and for releasing said member.

3. In a latch construction, a keeper, a latch member rockably mounted intermediate its ends, a keeper engaging portion on one end of said latch, a weight on the other tending to rock the same into latching position and a member secured to the weighted end of the said latch for manually rocking the latch 65 into latching position.

4. In a latch construction, a keeper, a latch member rockably mounted intermediate its ends, said latch member being weighted at one end and formed with a keeper engaging 75 portion at the other whereby said latch member is normally urged in latching direction and a flexible member secured to the weighted end of the latch member for manually rocking the latching member into latching position.

5. In a latch construction, a keeper, a latch member rockably mounted intermediate its ends, a keeper engaging portion on one end of said latch and a weight on the other tending to rock the same into latching position, and a single flexible member for manually 85 rocking the said latch member in either direction about its pivot, said flexible member having a free end whereby the same may be 90 actuated.

6. In a latch construction, a keeper, a latch member rockably mounted intermediate its ends, a keeper engaging portion on one end of said latch and a weight on the other 95 tending to rock the same into latching position and an operating member having a free end and having its other end connected to said latch member on each side of its support for manually rocking the same into operative and inoperative position.

7. In a latch construction, a keeper, a latch member, cooperating surfaces on the keeper and the latch member respectively for effecting a wedging action between the 105 same and an operating member secured at a plurality of points to said latch member, said operating member having a free end for actuating the same.

8. In a latch construction, a keeper, a 110 latch member, cooperating surfaces on the keeper and the latch member for effecting a preliminary latching engagement between the same, gravity actuated means for facilitating the preliminary latching engagement 115 of the latch member with the keeper, additional co-operating surfaces on the keeper and the latch member for effecting a wedging action between the same, and manually actuated means for producing the said wedging action between the keeper and the latch member.

In testimony whereof I affix my signature.

HAROLD F. WARDWELL.
